CAR TRUCK

Charles L. Heater, Chicago, Ill., assignor to American Steel Foundries, Chicago, Ill., a corporation of New Jersey

Application November 14, 1941, Serial No. 419,104

18 Claims. (Cl. 105—197)

My invention relates to railway car trucks and particularly to a well known form of such car truck which utilizes truss type side frames and a connecting bolster extending in the central bolster openings of the opposite frames.

In this particular form of car truck a portion of the springs are housed in the tension member beneath the bolster opening and another portion of the springs are seated on the tension member at the bottom of the bolster opening. The springs on the upper level directly engage the bolster and spring seats therefor are afforded on the inner face of the top wall of the bolster end; while legs or extensions are provided on the bottom of the bolster as a means of engaging the springs on the lower level, said legs extending through openings provided therefor in the spring seat or top chord of the tension member of the side frame.

Certain modifications of said car truck have been devised wherein friction absorbing devices are interposed between the downwardly projecting legs on the bolster end and the lower level springs, said devices comprising friction shoes actuated by said bolster for engagement with friction means supported on the lateral walls of the tension member.

The general object of my invention is to devise a practical and highly efficient form of friction device for such a car truck as that just described utilizing resilient means to control the amount of friction developed by the friction absorbing device.

Expressed in another way it is an object of my invention to devise a form of friction control for such a car truck as that described wherein the amount of friction to be developed may be fixed within predetermined reasonable limits and wherein resilient means may be utilized to effect said control.

Still another object of my invention is to afford a means of housing a resilient member suitable for accomplishing the above described purpose within the limits prevailing and at the same time to provide solid protection for said resilient means.

Yet another object of my invention is to devise a means of stabilizing the relative lateral motion between the bolster and side frame of such a car truck as that described.

A yet different object of my invention is to devise means in such a car truck as that referred to which may be effective not only to resist lateral motion of the bolster with respect to the frame but also may definitely limit the extent

thereof and at the same time afford means for snubbing the vertical movements of said bolster with respect to the supporting frame.

In the drawings, Figure 1 is a fragmentary side elevation of a car truck embodying my invention.

Figure 2 is a sectional view through the bolster and side frame structure shown in Figure 1, the section being taken substantially in the vertical planes indicated by the line 2—2 of Figure 1.

Figure 3 is a fragmentary horizontal sectional view taken through the truck structure shown in Figures 1 and 2, the section being taken approximately in the planes indicated by the line 3—3 of Figure 2.

Figure 4 is a plan view of my novel form of friction plate the view being taken from the outer face thereof. Figure 4A is a top plan view thereof, and Figure 4B a side elevation.

Describing the structure in detail, my novel arrangement may be applied to a railway car truck comprising a side frame of truss type having a compression member 2 and a tension member 4 with spaced integral columns 6, 6 defining with said members a central bolster opening 8 and spaced window openings 10, 10. The compression member 2 above the bolster opening 8 may be of box-section and the tension member below said opening may likewise be of box-section but of relatively great depth as compared with said compression member. Said box-section tension member may comprise the top chord 12 forming a spring seat for the top level springs diagrammatically indicated at 14, 14, and the bottom chord 16 affording spaced seats as at 18, 18 for the lower level springs diagrammatically indicated at 20, 20. Said box-section tension member also comprises the inboard wall or web 22 and the outboard wall 24 each of which webs 22 may conveniently be cored away at spaced points as at 26, 26 to facilitate inspection of the enclosed springs. The lower level springs 20, 20 may be spaced by a central upstanding lug 28 projecting therebetween and the outer wall 24 may be reinforced by the central vertical rib 30 as likewise the rib 32 may reinforce the inboard wall or web 22, said reinforcing ribs being provided centrally of the tension member to afford maximum support for the spring seat 12 thereabove.

The upper level springs 14, 14 are arranged longitudinally of the bolster as may best be seen in the sectional view of Figure 2, the upper ends of said springs being seated as at 34 and 36 against the inner face of the top wall 38 of the

bolster generally designated 40, the end of said bolster projecting through the bolster opening 8 and extending somewhat therewith in order to accommodate the outboard spring 14.

At each side of the bolster end may be formed a downwardly projecting leg or plunger member 42 and on the inboard and outboard faces of each of said legs may be formed upper and lower diagonally arranged surfaces which may engage respectively as at 44 and 46 with complementary spaced surfaces similarly arranged on the wedge friction shoes 48, 48 at opposite sides of said legs. Each wedge friction shoe 48 is substantially half cylindrical in form as may be seen from the sectional view of Figure 3, each shoe having a rectangular central opening or slot 50 on one face of which may be formed said before-mentioned spaced diagonally arranged faces. The outer cylindrical face of each friction shoe 48 may have frictional engagement as at 52 with the complementary surface 54 (Figure 4A) formed on the adjacent friction plate 56. The detailed form of each friction plate 56 is shown in Figure 4 wherein it may be noted that said plate is a casting of somewhat irregular form having the top flange 58 which may be recessed as at 60 in the top chord 12 of the tension member, the upper face of said flange being flush with the spring seat at 12 and thus held in proper position by the superposed spring group 14. At the lower end of each friction plate 56 may be formed a central lug 62 which may project into the adjacent opening 26 as additional convenient positioning means as well illustrated in Figure 1. Centrally of each friction plate 56 and on the face opposite the friction surface thereof may be formed a lug 64 serving as positioning means for the resilient member or rubber pad 66 one face of which may bear against the spring seat 68 formed for the purpose on said spring plate. The opposite face of the rubber pad 66 may seat as at 70 (Figure 2) in the shallow cavity formed therefor on the inner face of the adjacent side wall of the tension member and be positioned therein by the central lug 72.

It will thus be seen that a pair of wedge shoes 48, 48 is associated with the plunger 42 at each side of the bolster end and each shoe 48 has complementary arcuate face engagement with an adjacent friction plate 56 which is positioned with respect to the adjacent tension member wall against vertical movement with respect thereto but is permitted lateral movement with respect thereto. Such lateral movements are limited by the opposed lugs 64 and 72 which also serve as positioning means for the resilient means 66 compressed between each friction plate 56 and the adjacent side wall of the tension member. Normally each resilient member 66 is subjected to some slight compression as applied and this compression will be effective to maintain the friction plate in proper engagement with the adjacent friction shoe.

The engagement of the legs 64 and 72 will also be effective to limit the lateral motion of the bolster with respect to the side frame.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a car truck, a side frame having a bolster opening and a box-section tension member therebeneath with inboard and outboard walls and top and bottom chords defining spring seats, springs on said seats, friction means associated with each of said lower springs, a bolster directly seated on said top springs with spaced legs engaging said friction means respectively for actuation thereof, each of said friction means comprising spaced friction shoes mounted on the adjacent spring and in wedge engagement with the adjacent bolster leg, friction panels movably mounted on the respective tension member walls in abutment with said shoes, said wedge engagement of each leg with the adjacent shoes being effective to urge said shoes into frictional engagement with the adjacent friction panels, resilient means associated with each of said friction panels and operative to resist longitudinal and transverse movements thereof, and interengaging positioning means on each panel and the adjacent wall.
2. In a car truck, a side frame having a bolster opening and a box-section tension member therebeneath with inboard and outboard walls and top and bottom chords defining spring seats, springs on said seats, friction means associated with each of said lower springs, a bolster directly seated on said top springs with spaced legs engaging said friction means respectively for actuation thereof, each of said friction means comprising spaced friction shoes mounted on the adjacent spring and in wedge engagement with the adjacent bolster leg, friction panels movably mounted on the respective tension member walls in abutment with said shoes, said wedge engagement of each leg with the adjacent shoes being effective to urge said shoes into frictional engagement with the adjacent friction panels, resilient means associated with each of said friction panels and operative to resist longitudinal and transverse movements thereof, and interengaging positioning means on each panel and the adjacent wall.
3. In a railway car truck, a truss side frame having a tension member, a compression member, and spaced columns defining a bolster opening, said tension member having beneath said opening a box-section with spaced webs forming top and bottom spring seats, springs on said seats, friction shoes seated on the springs on said bottom spring seat, a bolster extending into said opening and seated on said top springs with spaced legs projecting through said top seat for wedge engagement with said shoes, each of said friction shoes cooperating with friction means mounted in the adjacent side wall of said tension member, each of said friction means comprising a friction panel supported on and laterally movable with respect to the adjacent tension member wall, and resilient means under compression between said panel and said wall.
4. In a railway car truck, a truss side frame having a tension member, a compression member, and spaced columns defining a bolster opening, said tension member having beneath said opening a box-section with spaced webs forming top and bottom spring seats, springs on said seats, friction shoes seated on the springs on said bottom spring seat, and a bolster extending into said opening and seated on said top springs with spaced legs projecting through said top seat for wedge engagement with said shoes, each of said friction shoes cooperating with friction means mounted in the adjacent side wall of said tension member, each of said friction means com-

prising a friction panel removably and resiliently supported on the adjacent tension member wall.

5. In a railway car truck, a side frame having a central bolster opening defined in part by spaced columns and a tension member, said tension member having a box-section with top and bottom chords and inboard and outboard walls, springs on said chords, friction shoes seated on said bottom springs, a bolster seated on said top springs and having spaced means projecting through said top chord for wedge engagement with the friction shoes associated with the respective bottom springs, friction panels mounted in said inboard and outboard walls adjacent the respective shoes, resilient means under compression between each friction panel and the adjacent wall, and interengaging positioning means on each panel and the associated wall.

6. In a railway car truck, a side frame having a bolster opening, a tension member beneath said opening having a box-section with inboard and outboard walls and top and bottom chords defining upper and lower spring seats, springs on said seats, a bolster projecting into said opening and directly supported on said upper springs and having downwardly projecting legs cooperating with friction means associated with each of said lower springs, each of said friction means comprising friction shoes seated on the adjacent spring and in wedge engagement with the adjacent bolster leg, friction panels mounted on the respective tension member walls in engagement with said shoes, and resilient means under compression between each panel and the adjacent wall.

7. In a car truck, a side frame having a bolster opening and a box-section tension member therebeneath with inboard and outboard walls and top and bottom chords defining spring seats, springs on said seats, friction means associated with each of said lower springs, a bolster directly seated on said top springs with spaced legs engaging said friction means respectively for actuation thereof, each of said friction means comprising spaced friction shoes mounted on the adjacent spring and in wedge engagement with the adjacent bolster leg, friction panels movably mounted on the respective tension member walls in abutment with said shoes, said wedge engagement of each leg with the adjacent shoes being effective to urge said shoes into frictional engagement with the adjacent friction panels, and resilient means supported by said frame and operable to resist longitudinal and transverse movements of said panels.

8. In a railway car truck, a side frame having a central bolster opening defined in part by spaced columns and a tension member, said tension member having a box-section with top and bottom chords and inboard and outboard walls, springs on said chords, friction shoes seated on said bottom springs, a bolster seated on said top springs and having spaced means projecting through said top chord for wedge engagement with the friction shoes associated with the respective bottom springs, friction panels mounted in said inboard and outboard walls adjacent the respective shoes, and nonmetallic resilient means under compression between each friction panel and the adjacent wall.

9. In a railway car truck, a side frame having a bolster opening, a tension member beneath said opening having a box-section with inboard and outboard walls and top and bottom chords defining upper and lower spring seats, springs

on said seats, a bolster projecting into said opening and directly supported on said upper springs and having downwardly projecting legs cooperating with friction means associated with each of said lower springs, each of said friction means comprising friction shoes seated on the adjacent spring and in wedge engagement with the adjacent bolster leg, friction panels movably mounted on the respective tension member walls in engagement with said shoes, and resilient means associated with said panels and operable to resist transverse movements of said bolster.

10. In a railway car truck, a side frame having a bolster opening, a tension member beneath said opening having a box-section with inboard and outboard walls and top and bottom chords defining upper and lower spring seats, springs on said seats, a bolster projecting into said opening and directly supported on said upper springs, and having downwardly projecting legs cooperating with friction means associated with each of said lower springs, each of said friction means comprising spaced friction shoes seated on the adjacent spring in wedge engagement with the adjacent bolster leg, and friction panels resiliently mounted on each wall of said tension member in frictional engagement with the respective shoes, each of said panels having a top flange recessed in said top chord and coplanar with the top surface thereof.

11. In a car truck, a side frame having a bolster opening and a box-section tension member therebeneath with inboard and outboard walls and top and bottom webs defining spring seats, a spring on each of said seats, friction means associated with the spring on said lower seat, a bolster directly seated on said top spring and having means actuating said friction means, said friction means comprising spaced friction shoes, and friction panels resiliently mounted on the respective tension member walls in engagement with said shoes, said bolster actuating means having wedge engagement with said shoes to urge them respectively into engagement with the adjacent panels.

12. In a car truck, a side frame having a bolster opening and a box-section tension member therebeneath with inboard and outboard walls and top and bottom webs defining spring seats, a spring on each of said seats, friction means associated with the spring on said lower seat, a bolster directly seated on said top spring and having means actuating said friction means, said friction means comprising spaced friction shoes, and friction panels resiliently mounted on the respective tension member walls in engagement with said shoes, said shoes having wedge engagement with said bolster actuating means.

13. In a car truck, a side frame having a bolster opening and a box-section tension member therebeneath with inboard and outboard walls and top and bottom chords defining spring seats, springs on said seats, friction means associated with each of said lower springs, a bolster directly seated on said top springs with spaced legs engaging said friction means respectively for actuation thereof, each of said friction means comprising spaced friction shoes mounted on the adjacent spring and in wedge engagement with the adjacent bolster leg, and friction panels resiliently mounted on the respective tension member walls in abutment with said shoes.

14. In a railway car truck, a truss side frame having a tension member, a compression member, and spaced columns defining a bolster open-

ing, said tension member having beneath said opening a box-section with spaced webs forming top and bottom spring seats, springs on said seats, friction shoes seated on the springs on said bottom spring seat, and a bolster extending into said opening and seated on said top springs with spaced legs projecting through said top seat for wedge engagement with said shoes, each of said friction shoes cooperating with friction means resiliently mounted in the adjacent side wall of said tension member.

15. In a railway car truck, a side frame having a central bolster opening defined in part by spaced columns and a tension member, said tension member having a box-section with top and bottom chords and inboard and outboard walls, springs on said chords, friction shoes seated on said bottom springs, a bolster seated on said top springs with spaced means projecting through said top chord for wedge engagement with the friction shoes associated with the respective bottom springs, and friction panels resiliently mounted in said inboard and outboard walls adjacent the respective shoes.

16. In a car truck, a side frame having a bolster opening and a box-section tension member therebeneath with inboard and outboard walls and top and bottom webs defining spring seats, a spring on each of said seats, friction means associated with the spring on said lower seat, and a bolster directly seated on said top spring and

having means actuating said friction means, said friction means comprising resilient means operable to resist transverse movements of said bolster.

- 5 17. In a car truck, a side frame having a bolster opening and a box-section tension member therebeneath with inboard and outboard walls and top and bottom chords defining spring seats, springs on said seats, friction means associated with each of said lower springs, and a bolster directly seated on said top springs with spaced legs engaging said friction means respectively for actuation thereof, said friction means comprising resilient pads associated with said walls and adapted to resist transverse movements of said bolster in compression and longitudinal movements thereof in shear.
- 10 18. In a railway car truck, a side frame having a bolster opening, a tension member beneath said opening having a box-section with inboard and outboard walls and top and bottom chords defining upper and lower spring seats, springs on said seats, a bolster projecting into said opening and directly supported on said upper springs, and having downwardly projecting legs cooperating with friction means associated with each of said lower springs, said friction means comprising resilient means adapted to control transverse movements of said bolster.
